LIQUEFIED GAS CONTAINER

Herbert M. Strong and Francis P. Bundy, Schenectady, N. Y., assignors to General Electric Company, a corporation of New York

Application July 11, 1952, Serial No. 298,326

4 Claims. (Cl. 220—9)

This invention relates to an insulated container for storing very cold liquefied gases such as methane, oxygen, natural gas and similar substances which must be cooled to an extremely low temperature in order to enable them to be stored at atmospheric pressure.

The storage of large quantities of very cold liquefied gases is of considerable importance in our present day technology. The efficiency and the economic value of such storage procedure depends heavily upon the evaporation losses resulting from heat leakage through the walls of the storage tank as well as upon the cost and upkeep of the tank.

Storage tanks in current use for liquefied gas usually consist of double walled spherical or cylindrical tanks in which the space between the walls is filled with finely divided pottery materials such as kieselguhr, charcoal, and similar materials, and the space is evacuated to a rough vacuum of about 100 to 1000 microns Hg pressure. The weight of the inner tank and its contents is supported by tie rods or pads of material different from the insulation filling material which extend between the inner and outer shells. The thickness of the insulating layer is usually 6 to 12 inches in the larger tanks and the average heat leakage rate with liquid methane, which boils at -161.5° C., at normal atmospheric air temperature outside is about 1-2 B. t. u. per hour per sq. ft. of container area.

It is an object of this invention to provide a liquefied gas container in which the heat loss through the walls is of the order of 0.2-0.4 B. t. u. per hour per square foot of container area.

It is another object of the invention to provide a storage tank for liquefied gas wherein a comparatively thin blanket of mineral insulating fibers restricts the flow of heat through the container.

It is a further object of the invention to provide a liquefied gas container wherein radiation losses are held to a minimum by a pair of reflective surfaces interposed in the path of heat flow.

It is a still further object of the invention to provide a liquefied gas storage tank wherein heat losses are restricted by a combination of a pair of reflective surfaces and a blanket of mineral insulating fibers.

Briefly stated, in accordance with one aspect of this invention, a liquefied gas container comprises a double-walled vessel having a gas-tight space of substantially uniform thickness between the walls, a blanket of mineral insulating fibers in the evacuated space, and a surface of high reflectivity in the space positioned in proximity to the inner wall, the outer surface of which is also highly reflective whereby the two reflective surfaces face each other.

Referring to the drawing, the container is seen to consist of a double-walled vessel having an outer tank 10 completely enclosing an inner tank 11 which is spaced a short distance from the outer tank 10 whereby the tanks define a space 12 of substantially uniform thickness. Connections between the tanks 10 and 11 are in gas-tight

2

relationship and the evacuated space 12 is maintained at a pressure of less than 1 mm. Hg and preferably at a pressure of less than 100 microns of Hg. We have found it possible to maintain a pressure as low as 1 micron Hg for a protracted period of time. There is no critical pressure level. Heat loss diminishes as pressure decreases. Accordingly, we prefer to maintain the pressure within the evacuated space 12 at the lowest feasible level.

10 The evacuated space 12 is occupied by a blanket 13 of mineral insulating fibers such as slag wool, asbestos, aluminum oxide, and siliceous materials such as glass fibers and quartz fibers. We prefer to use glass fibers in accordance with the structure disclosed and claimed in our copending application, Serial No. 236,788, filed July 14, 1951, and assigned to the same assignee as the present application. In accordance with our copending application superior resistance to heat transfer is provided by a blanket of glass fibers randomly oriented with their axes in planes generally parallel to the plane of the nearest section of container wall. In other words, the axes are perpendicular to the direction of heat transfer taking place through the container walls. We prefer to use glass fibers having a diameter of less than 0.001" and preferably of the order of 0.0002".

20 We prefer to precompact the blanket of glass fibers in accordance with the method disclosed in Janos application Serial No. 236,971, filed July 16, 1951, now abandoned, and assigned to the same assignee as the present application. In accordance with the Janos method we compress a blanket of glass fibers to a density of between 10 pounds and 30 pounds per cubic foot and heat them to a temperature just below the softening point of the glass while in this compressed condition. The blanket 25 is then allowed to cool while in the compressed state. The subsequent release of the compression is then of little effect as the fibers retain their compressed shape.

30 The blanket 13 of mineral fibers is positioned between the outer wall 10 and a metal surface 14 spaced in proximity to the wall of the inner tank or container 11. The surface 14 is made highly reflecting on the side facing the wall of the inner tank 11 and the wall of the inner tank 11 facing the surface 14 is also made highly reflecting. The effect of these reflecting surfaces is to decrease the thermal radiation emissivity. The surface 14 35 may be a very thin metal sheet since it does not serve as a supporting member. It is desirable that it be as close as possible to the inner tank 11 while yet maintaining a slight distance apart therefrom. A distance of the order of 0.001" is desirable but in practice the distance is greater than this and not uniform over the entire surface.

40 The metal surface 14 surrounds a major portion of inner tank 11 and is omitted around a portion of the bottom of the container structure indicated at 15. This omitted portion of surface 14 defines at least one open area adjacent the base of inner tank 11. In this section the blanket of mineral insulating fiber 13 is made slightly thicker so that it acts as a support for the inner tank 11.

45 A corrugated bellows 16 of thin metal of low thermal conductivity forms the passage between the inner tank and outer tank constituting the container. The bellows 16 terminates in a connecting ring 17 in which a plug 18 of material of low thermal conductivity is embedded. A pipe 19 extends through the plug 18 and is utilized to introduce or remove liquid from the interior of the container.

50 For large installations an outlet 20 having a valve 21 is provided from the space 12 to which a vacuum pump (not shown) may be connected. In this way the container 55 may be periodically tested and evacuated if necessary.

55 In the embodiment shown the container may be con-

sidered as taking the form of a sphere or a cylinder positioned on its side. In either of these forms it is necessary to provide a supporting base 22 with vertical supporting members 23 to support the container. However, it should be understood that other shapes may be used with our invention including large, upright cylinders requiring no supporting members to position them off the ground.

The metal out of which the tanks 10 and 11 are formed must be of a type which resists the diffusion of gases therethrough. Most metals have this characteristic and may be utilized in accordance with our invention. However, we prefer to use metals having a high resistance to corrosion as well as low thermal conductivity. The various stainless steels on the market answer this requirement admirably. Carbon steels may be used provided they are given a protective coating such as vitreous enamel or an electroplated metal to prevent the formation of rust. Alloys such as Monel metal, Invar, and many others are also satisfactory.

While the present invention has been described with reference to particular embodiments thereof, it will be understood that numerous modifications may be made by those skilled in the art without actually departing from the invention. Therefore, we aim in the appended claims to cover all such equivalent variations as come within the true spirit and scope of the foregoing disclosure.

What we claim as new and desire to secure by Letters Patent of the United States is:

1. A liquefied gas container comprising an inner metal tank positioned within an outer metal tank, said tanks being in spaced relation whereby there is an evacuated space between the walls of said tanks, the surface of said inner tank facing said evacuated space being highly reflective, a member positioned within said evacuated space and surrounding a major portion of said inner tank and defining at least one open area adjacent the base of said inner tank, said member being spaced from said inner tank and said outer tank and having a highly reflective surface facing the highly reflective surface of said inner tank, a blanket of clean, binder-free mineral insulating fibers compacted to a density of more than 10 pounds per cubic foot positioned adjacent the inner surface of said outer tank and extending to said member and to the inner wall of said inner tank in the region of the area defined by said member, said blanket constituting a supporting surface for said inner tank.

2. A liquefied gas container comprising an inner metal tank positioned within an outer metal tank, said tanks being in spaced relation whereby there is an evacuated space of substantially uniform thickness between the walls of said tanks, the surface of said inner tank facing said evacuated space being highly reflective, a member positioned within said evacuated space and surrounding a major portion of said inner tank and defining at least one open area adjacent the base of said inner tank, said member being spaced from said inner tank and said outer tank and having a highly reflective surface facing the highly reflective surface of said inner tank, a blanket of clean, binder-free mineral insulating fibers compacted to a density of more than 10 pounds per cubic foot positioned adjacent the inner surface of said outer tank and

extending to said member and to the inner wall of said inner tank in the region of the area defined by said member, said blanket constituting a supporting surface for said inner tank.

- 5 3. A liquefied gas container comprising an inner metal tank positioned within an outer metal tank, said tanks being in spaced relation whereby there is an evacuated space between the walls of said tanks, the surface of said inner tank facing said evacuated space being highly reflective, a member positioned within said evacuated space and surrounding a major portion of said inner tank and defining at least one open area adjacent the base of said inner tank, said member being spaced from said inner tank and said outer tank and having a highly reflective surface facing the highly reflective surface of said inner tank, a blanket of clean, binder-free mineral insulating fibers compacted to a density of from 10 to 30 pounds per cubic foot positioned adjacent the inner surface of said outer tank and extending to said member and to the inner wall of said inner tank in the region of the area defined by said member, said blanket constituting a supporting surface for said inner tank.
- 10 4. A liquefied gas container comprising an inner metal tank positioned within an outer metal tank, said tanks being in spaced relation whereby there is an evacuated space between the walls of said tanks, the surface of said inner tank facing said evacuated space being highly reflective, a member positioned within said evacuated space and surrounding a major portion of said inner tank and defining at least one open area adjacent the base of said inner tank, said member being spaced from said inner tank and said outer tank and having a highly reflective surface facing the highly reflective surface of said inner tank, a blanket of clean, binder-free mineral insulating fibers compacted to a density of more than 10 pounds per cubic foot positioned adjacent the inner surface of said outer tank and extending to said member and to the inner wall of said inner tank in the region of the area defined by said member, said fibers being randomly oriented with their axes in planes generally perpendicular to the direction of heat flow through said blanket, said blanket constituting a supporting surface for said inner tank.
